UNITED STATES PATENT OFFICE.

SAMUEL C. FRANKS, OF FREMONT, OHIO.

WINDOW.

969,778.

Specification of Letters Patent. Patented Sept. 13, 1910.

Application filed August 18, 1909. Serial No. 513,385.

To all whom it may concern:

Be it known that I, SAMUEL C. FRANKS, a citizen of the United States of America, residing at Fremont, in the county of San-dusky and State of Ohio, have invented cer-tain new and useful Improvements in Win-dows, of which the following is a specifi-cation.

This invention relates to windows, the ob-10 ject of said invention being to provide a de-vise of this character so arranged that it may be opened or closed by a horizontal sliding movement, by a horizontal swinging movement, or by being raised or by being 15 lowered, whereby almost any adjustment of the window may be secured.

Further objects and advantages of the in-vention will be set forth in the detailed de-scription which now follows.

20 In the accompanying drawing, Figure 1 is an inside view of a portion of the wall of a frame building showing the window mounted therein, Fig. 2 is a vertical section upon line 2—2 of Fig. 1, showing the win-dow swung open, Fig. 3 is a horizontal sec-tion upon line 3—3 of Fig. 1 looking in the direction of the arrow, and, Fig. 4 is a hori-zontal section upon line 4—4 of Fig. 1 look-ing in the direction of the arrow.

30 Like numerals designate corresponding parts in all of the figures of the drawing.

Referring to the drawing, the numerals 5 de-signate the studding of the building be-tween which the lintel 6 and sill 7 extend. 35 Stop strips 8 and 9 are arranged respec-tively above and below these members and serve a purpose hereinafter described. The window frame 10 is secured to the studding and a sub-sill 11 which comprises a depend-ing filling block 12 is hingedly connected by horse-shoe hinges 13 to the lower sill of the window in such manner that this sub-sill may either be swung inwardly to cause the block 12 to lie in a cut-out portion 14 of the 45 window sill, or may be swung outwardly to remove said block from said cut-out portion.

By referring to Fig. 4, it will be seen that a channel 15 is formed in the sill. This channel at one end extends to and is in com-munication with the cut out portion 14 of the sill. A pivot receiving recess 16 is formed in that portion of the lower sill that lies inside of the cut-out portion 14. A win-dow 17 which is here shown as provided 55 with two panes of glass 18, though any number of panes may be used, carries a

pivot 19 which slides in the channel 15, said channel and a channel 22 hereinafter de-scribed being preferably lined with metal indicated at 20.

60 By referring to Fig. 3, it will be seen that the lintel is cut out at 21 and is channeled at 22 for the reception of a roller 23 mount-ed upon the upper edge of the window sash 24. Ordinarily, the window slides in the 65 channels 15 and 22 and is prevented from moving over into alinement with the cut-out portion 14 of the sill by the sub-sill and by a filling strip 25. It will therefore be apparent that when the window is slid back 70 into the recess 26, the entire opening within the window frame is left clear for ventila-tion, or if it be desired, to pass furniture in or out of said opening.

75 After the window has been moved to the position illustrated in Fig. 1, it may be elevated, the upper end of the window sash at that time passing through the cut-out portion 21 of the lintel. A catch 27 of the usual and well known construction serves 80 to retain the window in such elevated posi-tion. Hand grasps 28 and 29 are provided upon the transom bar and lower rail of the sash to enable the operator to readily handle said sash. If it be desired to lower the 85 window from the top, the sub-sill is swung inwardly upon its hinges 13 to bring the block 12 out of the cut-out portion 14 of the sill. The operator, by grasping the 90 hand grasp 29, may then draw the lower 95 edge of the sash inwardly and let said sash descend through the cut-out portion 14 of the sill until said sash rests upon the stop strip 9. Since this raising of the window and the lowering thereof and the sliding 100 movement thereof, all take place within the line of the outer face of the window frame, it will be apparent that all of these move-ments may be accomplished without inter-ferring with a screen (not shown) arranged 105 across the outer face of the window frame. By removing the strip 25 and by swinging the sub-sill inwardly as heretofore described, the window sash may be drawn inwardly until its pivot 19 rests in the socket 16 and until its roller 23 rests in the pocket 30 110 formed in the under face of the lintel (see Fig. 3). The window may then be rocked or swung upon its central pivots 23 and 19 to the position illustrated in Fig. 2.

By constructing a window as herein shown and described capable of being

opened and adjusted in so many ways, the necessity of forming the sash in two sections as has heretofore been done is obviated. Consequently the use of parting strips, sash 5 weights, and cords, and many other parts, is rendered unnecessary. This results in greatly cheapening the cost of the window as a whole and since the sub-sill and retaining strip 25 force the window sash firmly 10 forward, the window is held against rattling and the entry of dust, wind, or rain, is effectually prevented. Furthermore, the pivotal mounting of the window by which it may be swung entirely around to bring the outer 15 face of the window sash toward the inside of the room, renders it possible to clean the glass of the window without exposing the person cleaning the window to the danger of falling, such as is the case when the window 20 cleaner must get out upon the window sill.

An additional advantage of this structure resides in the fact that the window is closed while being cleaned. This is of importance 25 in very cold weather.

From the foregoing description, it will be seen that simple and efficient means are herein provided for accomplishing the objects of the invention, but while the elements 30 shown and described are well adapted to serve the purposes for which they are intended, it is to be understood that the invention is not limited to the precise construction set forth but includes within its 35 purview such changes as may be made within the scope of the appended claims.

Having described my invention, what I claim is:

1. The combination with a window frame, 40 of a sash mounted for lateral sliding movement in its own plane, into and out of said frame, said sash closing the opening of said frame when moved thereinto, and said sash passing through an opening formed in one 45 side of the window frame when moved out

of said frame, and means at the top and bottom of the sash for pivotally mounting said sash adjacent to its limit of movement into said window frame.

2. The combination with a window frame, 50 of a sash mounted for lateral sliding movement in its own plane, into and out of said frame, said sash closing the opening of said frame when moved thereinto, and said sash passing through an opening formed in one 55 side of the window frame when moved out of said frame, means at the top and bottom of the sash for pivotally mounting said sash adjacent to its limit of movement into said window frame, there being an opening 60 formed in the top of said window frame through which said sash may be raised, and means for holding said sash in an elevated position.

3. The combination with a window frame, 65 of a sash mounted for lateral sliding movement in its own plane, into and out of said frame, said sash closing the opening of said frame when moved thereinto, and said sash passing through an opening formed in one 70 side of the window frame when moved out of said frame, means at the top and bottom of the sash for pivotally mounting said sash adjacent to its limit of movement into said window frame, there being an opening 75 formed in the top of said window frame through which said sash may be raised, means for holding said sash in an elevated position, and there being an opening formed in the bottom of said window frame through 80 which said sash may be lowerd, and means for limiting the downward movement of said sash.

In testimony whereof I affix my signature in presence of two witnesses.

SAMUEL C. FRANKS.
